US00D546970S

(12) **United States Design Patent** (10) **Patent No.:** **US D546,970 S**
Howe et al. (45) **Date of Patent:** **** Jul. 17, 2007**

(54) **DOOR FOR A SHED**

(75) Inventors: **Rich Howe**, Pleasant View, UT (US);
Kent Ashby, Logan, UT (US); **Neil Watson**, Layton, UT (US); **Brent Steed**, Syracuse, UT (US)

(73) Assignee: **Lifetime Products, Inc.**, Clearfield, UT (US)

(**) Term: **14 Years**

(21) Appl. No.: **29/259,983**

(22) Filed: **May 17, 2006**

(51) **LOC (8) Cl.** **25-02**

(52) **U.S. Cl.** **D25/49; D25/48**

(58) **Field of Classification Search** D25/47, D25/48, 49, 33, 14, 22; 52/79.1, 90.1, 79.5, 52/64; 160/DIG. 8

CLAIM

The ornamental design for door for a shed, as shown and described.

DESCRIPTION

FIG. 1 is a front elevation view of a door for a shed; FIG. 2 is a perspective view with one door slightly ajar; FIG. 3 is a perspective view with all doors partially ajar; and, FIG. 4 is a perspective view with all doors fully opened. The broken lines shown in the figures are for illustrative purposes only and form no part of the claimed design.
